UNITED STATES PATENT OFFICE

2,063,316

WINDOW STRUCTURE

Edward G. La Fontaine, Brooklyn, N. Y.

Application November 13, 1935, Serial No. 49,527

4 Claims. (Cl. 292—74)

The object of my invention is to provide a window frame and sash construction involving novel features without sacrificing any of the advantages of constructions now in use, the construction of the improved frame and sash being simple, durable, and comparatively inexpensive to manufacture.

A further object is to construct a window frame and sashes therefor with various features to make the construction more weatherproof than the ordinary type of double hung sash windows now in use.

A further object is to provide an improved method of holding the sashes in selected positions and eliminate the heretofore used sash weights and provide means to prevent window rattle and noises as well as sticking of the sashes relative to the frame.

Another object is, by means of elimination of sash weights and the necessary boxes therefor, to make it possible to use a narrower window trim which enhances the architectural beauty of the construction.

With these and other objects in view my invention consists in the construction, arrangement and combination of various parts of my device as hereinafter more fully set forth and illustrated in the accompanying drawing in which preferred embodiments of the invention are shown, and in which—

Fig. 1 is longitudinal sectional fragmentary view of a window frame with double hung sashes in a closed position, disclosing a very simple form of holding sashes in selected positions within the frame;

Fig. 2 is an enlarged horizontal sectional view along the plane of line 2—2 in Fig. 1 except that parts of the sashes are shown one immediately behind the other;

Fig. 3 is a view similar to Fig. 1, but showing a modified construction of sashes;

Fig. 4 is an enlarged horizontal sectional view along the plane of line 4—4 in Fig. 3 also with parts of the sashes shown one immediately behind the other;

Fig. 5 is a sectional view similar to Fig. 4 with a modified form of sash holding means;

Fig. 6 shows a fragmentary longitudinal sectional view of a window frame with an elevational view, partly in section, of part of the sash with still further modified sash holding means, and

Fig. 7 is a plan view of the arrangement shown in Fig. 6.

Like characters of reference denote similar

parts throughout the several views and the following specification.

In Fig. 1 is shown, more or less diagrammatically, a fragmentary part of a window frame 10, having the right-hand portion which is not shown, preferably symmetrical and the same as the shown left-hand portion. 11 are side jambs of the frame. 12 is a top jamb and 13 a bottom jamb or sill. The side jambs 11 are provided with two parallel grooves 14 in the case of double hung windows which style is illustrated in the figure. 15 is a parting bead between the grooves 14.

Slidably disposed within the frame 10 are two sashes 16, having top rails 17, bottom rails 18 and styles 19. The styles 19 of the sashes 16 are slidably disposed within the grooves 14 of the frame 10 and separated from each other by the parting bead 15. The sashes have each projecting ledges 20 along their styles 19, opposite each other, which partly project over the parting beads 15, as clearly shown in Fig. 2, to provide additional weather protection besides the overlap of the sashes within the grooves.

21 are flat friction strips disposed within the grooves 14 of the frame, preferably one within each groove. These strips bear against the styles 19 of the sashes by virtue of the pressure of coil springs 22 in recesses 23 of the frame 10. These springs are provided for preferably near the top and bottom ends of the strips 21.

The operation of a window made in accordance with the construction just described, is quite simple and does not vary from one employing the usual form of sash weights. The window sashes can be moved quite easily and by reason of the friction exerted towards the styles of the sashes, they will remain in any selected position without dropping, the tension of the springs having been so calculated that the friction will be greater than the weight of the sashes. There is further triple protection against weather with the construction of sashes shown, namely contact with two sides of each groove and the additional ledge 20 alongside the style of each sash.

In Figs. 3 and 4 is shown a slight modification of the construction shown in Figs. 1 and 2. The friction strip 21 is provided with metal discs 24 suitably secured to the strip, so that the springs 22 can be inserted into their recesses 23 in the frame without removing the sashes. The extreme outside of the styles 19 of the sashes are slightly tapering as shown at 19a. By so shaping the sashes, greater friction is exerted against their sides as is obvious from an inspection of 55

the figure. The small end of the sash may be either at the top or at the bottom, as preferred, in either case, the flat friction strip 21 adjusts itself to the slightly inclined outline of the sash.

5 In Fig. 5 is shown a further modification in the provision of a tongue 21a in the strip 21 and a corresponding groove 18b in the style 18 of the sash to provide additional weather protection. In all other respects the construction may be 10 identical with those shown and described herein in Figs. 1 to 4.

In Figs. 6 and 7 is illustrated another modification of the sash for the purpose of facilitating the manufacture of the sashes and their insertion, as a unit with the friction strips, into the 15 grooves of the frame. In these figures, the sash 16 is rectangularly shaped, as for instance in Fig. 1. Both top rail 17 and bottom rail 18 are grooved at 25 to receive at each end an angle 20 plate 26 having one of its legs 26a slidably disposed within the groove 25. 27 is a flat friction strip adapted to slide within the groove 14 of frame 10. The strip 27 is fastened to and between the angle plates 26 at each side of the 25 sash, so that another leg 26b of the plate 26 is set into the end of strip 27 to present a smooth surface toward the wall of the groove 14 and for all practical purposes forms an integral unit with the two angle plates 26 at its ends. Each leg 26a 30 of the plate 26 is provided with a slot 26c for the reception of a pin 28 secured to the top rail 17 and bottom rail 18, respectively. The coil springs 22 are inserted into grooves 21a in the friction strip 27 and bear against the style 18 of the sash. 35 With this embodiment of my invention, the friction strips form a unit with the sash, the pins 28 preventing the strips becoming disengaged from the sash, while permitting the springs to act against the strips without restraint. Sashes made in accordance with this construction are 40 most economically manufactured as units and can readily be inserted into their frames.

It is obvious that the principles of my invention

are equally as applicable to single hung windows, such as windows in railroad coaches and the like, and that either of the embodiments shown and described may be successfully used for such purposes. 5

It is understood that various changes of form, proportions and minor details of construction may be resorted to without departing from the principles or sacrificing any of the advantages of the invention as defined in the appended 10 claims.

What I claim as new, is:

1. In a window structure, a frame having 15 grooves, a sash slidably disposed within the grooves having its width narrower at one end than at its other end, friction strips within the grooves, and springs against the friction strips to cause the strips to bear against styles of said sash.

2. In a window structure, a frame having 20 grooves, a sash having converging styles slidably disposed within the grooves, friction strips within the grooves, and springs against the friction strips to cause them to frictionally engage the 25 said styles.

3. In a window structure, a frame having 30 grooves, a sash slidably disposed within the grooves having the distance between its styles less at one end than at its other end, friction strips within the grooves, the said strips and styles of the 35 said sash having tongue and groove joints between them, and springs against the said strips to cause them to frictionally engage the said styles.

4. In a window structure, a frame having 40 grooves, a sash having converging styles slidably disposed within the grooves, friction strips within the grooves, and springs against the said strips to cause them to frictionally engage styles of the said sash, the said strips having closed openings 45 for the insertion of the springs into recesses of said grooves.

EDWARD G. LA FONTAINE.
